UNITED STATES PATENT OFFICE.

MAURICE LACHMAN AND LAURENCE S. LACHMAN, OF NEW YORK, N. Y.

DESIGN FOR A FENCE.

No. 39,998.

Specification for Design.

Patented May 18, 1909.

Application filed March 22, 1909. Serial No. 485,131. Term of patent 14 years.

To all whom it may concern:

Be it known that we, MAURICE LACHMAN and LAURENCE S. LACHMAN, citizens of the United States, residing in New York city, county of New York, State of New York, have invented a new, original, and ornamental Design for Fences, of which the following is a specification, reference being had to the accompanying drawing, forming part thereof.

The figure is a plan view of a fence, showing our new design.

We claim:

The ornamental design for a fence as shown.

MAURICE LACHMAN.
LAURENCE S. LACHMAN.
